UNITED STATES PATENT OFFICE.

HENRY GEISENHÖNER, OF SCHENECTADY, NEW YORK, ASSIGNOR TO GENERAL ELECTRIC COMPANY, A CORPORATION OF NEW YORK.

ELECTRICAL HEATING APPARATUS.

1,406,550.

Specification of Letters Patent.

Patented Feb. 14, 1922.

Application filed June 21, 1920. Serial No. 390,507.

To all whom it may concern:

Be it known that I, HENRY GEISENHÖNER, a citizen of the United States, residing at Schenectady, in the county of Schenectady, State of New York, have invented certain new and useful Improvements in Electrical Heating Apparatus, of which the following is a specification.

This invention relates to electrical heating apparatus and more particularly to that type wherein material or articles are heated by the passage of an electric current therethrough.

One object of the present invention is to provide an apparatus of this character in which there are no movable parts designed to carry current.

Another object is to provide an electrical heating apparatus having a pair of stationary electrodes with means for forcing the material or articles to be heated against said electrodes.

My invention will be better understood from the following description taken in connection with the accompanying drawing, and its scope will be pointed out in the appended claims.

Referring to the accompanying drawing, Fig. 1 is a side elevation of a heating apparatus embodying my invention; Fig. 2 is a top plan view of the same, certain of the parts being broken away; Figs. 3, 3^a and 4 are detail views, showing modifications of the means for pressing an article against the electrodes; Fig. 5 is a side elevation of an apparatus similar to that shown in Fig. 1 but modified to provide for the support of the articles in a plane inclined to the horizontal; Fig. 6 is a front elevation of the apparatus shown in Fig. 5; Fig. 7 is a detail view of a modified form of article holder; Fig. 8 is a diagrammatic view showing the circuit connections for heating a considerable number of articles in series; Fig. 9 is a front elevation of yet another modified form of my invention; Fig. 10 is a side elevation of the form of the apparatus shown in Fig. 9; Fig. 11 is a diagrammatic view showing the circuit arrangement for the apparatus shown in Figs. 9 and 10, and Fig. 12 is a diagrammatic view showing a modified form of circuit arrangement.

Referring to Figs. 1 and 2 of the drawing, 10 represents a frame upon which is mounted a transformer formed of a primary wind-

ing 11 and a U-shaped secondary winding 12. Rod 13 connecting the top side bars of the frame 10 serves as a pivot for the arms 14 and pedals 15 pivoted at 16 and connected to the arms 14 through links 17 60 serve to move the arms about their pivotal support. Each of the arms carries at its outer end a presser head 18, which is adapted to engage an article to be heated. In order that the points of contact of the head 65 with the article may be varied, each head is adjustably secured to its arm by means of a screw 19. The heads 18 are preferably insulated from each other in any suitable way. Extending between the top side bars 70 of the frame 10 are two cross pieces 20 and 21. The cross piece 20 is secured rigidly to the frame and carries an electrode 22 in the form of a bar provided with a raised portion 23. This electrode is insulated from 75 the cross bar 20 and is electrically connected to one terminal 24 of the secondary winding 12. The cross piece 21 is adjustably secured to the side bars of the frame by means of wing bolts 25 which pass through slots 26 80 in the side bars. Electrode 27 formed with a raised portion 28 is carried upon the cross piece 21 and insulated therefrom and is connected by a flexible lead 29 to the opposite terminal 30 of the secondary winding. To 85 prevent the weight of the presser heads 18 from carrying them to a position to close the circuit between electrodes 22 and 27, a stop 31 is secured to the frame 10 to limit the upward movement of the pedals 15. 90

In practice the articles to be heated, such as rivets, bolts, and the like, are placed across the electrodes 22 and 27 in a manner shown in the drawing, the corresponding 95 pedals being depressed to lift the presser heads, which, when released, force the articles into firm contact with the electrodes. Each article completes a circuit through the secondary of the transformer and carries its portion of the total secondary current with 100 the result that it is heated to the desired temperature. Figs. 1 and 2 show means by which four articles may be heated in parallel in the circuit. The electrode 27 may be adjusted to accommodate articles of different 105 length.

The presser head, of course, may be dispensed with, if desired, and the ends of the lever arms arranged to force the articles into contact with the electrodes. Fig. 3 shows 110

the end 32 of the lever arm bent to engage the top of the article to be heated. Where the presser heads are omitted, the bolt or rivet may rest in grooves in the tops of the electrodes to prevent the same from slipping from under the ends of the lever arms as shown in Fig. 3, or the end of the presser arm may be broadened as in Fig. 3^a.

In some instances, particularly when the articles are to be heated to a very high temperature, it has been found that the pressure of the head 18 at a point between the electrodes tends to bend the articles. To avoid this, Fig. 4 shows the presser head formed as a yoke 33, pivoted at 34 to the lever arm and provided with two contact surfaces designed to engage the rivet at points directly above the electrodes.

In the form of my invention shown in Figs. 5 and 6, two of the side bars of the frame are extended upwardly at an incline to the vertical, as shown at 35 and 36. These extensions carry the fixed cross bar and the adjustable cross bar as in the form shown in Figs. 1 and 2. Secured to the adjustable cross bar and insulated therefrom is an electrode 37 which is provided with grooves 38 and 39 for the reception of the shanks of the rivets, bolts, or the like. Secured to the fixed cross piece and insulated therefrom are electrodes 40 and 41 which are likewise provided with grooves arranged in alignment with the grooves of the electrode 37. Electrode 40 is secured to one terminal and electrode 41 to the opposite terminal of the secondary winding of the transformer. The means for pressing the articles into contact with the electrodes consists of bell crank levers 42 formed as shown and pivoted at 43 to the frame of the apparatus. Pedals 44 pivoted to a cross rod 45 serve to operate said levers through the connecting rods 46. The contact forces of the presser arms are insulated from each other in any suitable manner, an insulating joint 42' being shown for this purpose. From the construction shown, it is apparent that the articles are connected in series in the circuit. When one article alone is being heated it is therefore necessary that some means be provided for completing the circuit across the gap caused by the absence of the other article. To accomplish this, the pedals 44 are extended at 47 and provided with weights 48 to cause the same normally to occupy a raised position with the result that the levers are constantly being forced toward a position in contact with the electrodes. In case it is desired to prevent the levers from closing the circuit as above set forth, an adjustable stop 49 secured across the frame of the apparatus serves as a limit to the upward movement of the pedals. It will be seen that the heads of the rivets shown in Figs. 5 and 6 engage the side of the raised portion

of the electrode 37 and are therefore prevented from slipping through the grooves. In case it is desired to heat rods which are not provided with heads, the electrodes 40 and 41 are preferably formed with shoulders 70 to engage the ends of the rods as is shown in Fig. 7. The provision of such shoulders on the electrodes does not prevent the use of the apparatus to heat articles without heads since the parts may be arranged to let the heads project over the upper edge of the upper electrode as in Fig. 5.

Among the advantages of the apparatus shown in Figs. 5 and 6 is the provision of a combined electrode and holder which is readily accessible for the insertion and removal of the articles to be heated and which is constructed and arranged to support the articles uniformly in the same position.

Fig. 8 shows a modification which may be applied to the form of heater shown either in Figs. 1 and 2 or 5 and 6 and which will enable a considerable number of rivets to be heated in series. In that figure, 50 and 51 are two electrodes connected to opposite terminals of the transformer secondary. 52, 53 and 54 are electrodes adapted each to engage a pair of rivets or the like and 55 and 56 are electrodes adapted to connect the ends 95 of rivets of adjacent pairs.

Figs. 9 and 10 of my invention disclose a form of apparatus particularly useful for heating soldering irons. In these figures a frame 57 carries a transformer which consists of a primary winding 58 and a secondary winding 59. The one terminal 60 of the secondary winding 59 is connected to a central electrode 61 which consists of a block of carbon or similar material 62, held 105 within a channel-shaped member 63. Member 63 is secured to the frame 57 by means of bolts 64 which pass through the opposite terminal 65 of the secondary winding of the transformer but are insulated therefrom at 110 66. These bolts likewise pass through insulating spacing blocks 66' and secure in contact with the terminal 65 of the transformer the cross connector 67 which connects the two end electrodes 68. These electrodes are also formed of carbon blocks indicated at 69 secured within channel-shaped members 70. Carbon blocks 62 and 69 are spaced some distance from one another and the upper portions of adjacent faces are cut away, as indicated at 71 for the reception of the soldering iron. The bolt 72 which secures the terminal 60 to the central electrode 61 also passes through and secures to the central electrode the upright 73. This upright 125 is suitably insulated from the central electrode and is formed at its upper end with cross piece 74 provided with openings 75 for the reception of the rods 76. Rods 76 carry weights 77 which are adapted to rest upon 130

the soldering irons and press them into contact with the electrodes. Brackets 78 shown in Fig. 10 assist in holding the soldering irons in place while being heated. The soldering irons in the apparatus shown in Figs. 9 and 10 are connected in parallel in the circuit as is shown in Fig. 11. The circuit connections may, however, be altered by omitting the cross connector 67 and connecting the terminals 60 and 65 to the outside electrodes, as is shown in Fig. 12 of the drawing, in which case the tools will be connected in series.

What I claim as new and desire to secure by Letters Patent of the United States, is:—

1. In an apparatus for heating an article by passing an electric current therethrough, a circuit, two electrodes connected to opposite terminals of the circuit and formed to constitute a bed for the support of the article and means not included in the circuit for engaging said article and forcing it into contact with the electrodes.

2. In an apparatus for heating an article by passing an electric current therethrough, a circuit, two electrodes connected to opposite terminals of the circuit and formed to constitute a bed for the support of the article and means not included in the circuit for engaging said article and pressing it into contact with the electrodes, said means comprising a lever arm and a presser head adjustably mounted on the lever arm to vary the point of application of pressure to the article.

3. In an apparatus for heating an article by passing an electric current therethrough, a circuit, two electrodes connected to opposite terminals of the circuit and formed to constitute a bed for the support of the article and means not included in the circuit for engaging said article and pressing it into contact with the electrodes, said means comprising an arm provided with a presser head.

4. In an electrical apparatus, the combination of upper and lower electrodes, both supported in an inclined plane, the upper elec-

trode being provided with a supporting groove, the lower electrode being provided with a supporting groove in alignment with the first mentioned groove, and one of said electrodes being provided with a surface arranged to engage the article to be heated, and prevent slipping thereof along the inclined surfaces of the electrodes.

5. In an apparatus for electrically heating articles, a source of current, a row of electrodes each of which is adapted to make contact with a pair of articles, a second row of electrodes, the end electrodes of said second row being connected to said source and each adapted to make contact with one article, the intermediate electrodes of said second row being adapted to make contact with one article of two adjacent pairs where- by said circuit is completed through all of said electrodes and articles in series, and means not included in the circuit for forcing said articles into contact with said electrodes.

6. A combination with two spaced electrodes formed with their adjacent faces cut away for the reception of an article to be placed between the electrodes, of means for forcing the article into contact with the electrodes.

7. A combination with a frame, of a transformer mounted on said frame, a series of spaced electrodes the adjacent faces of which are cut away for the reception of articles to be placed between the electrodes, an upright secured to one of the electrodes but insulated therefrom, a cross bar formed at the upper end of said upright and provided with openings, weights adapted to rest upon the articles when the same are in position between the electrodes, rods connected to said weights and passing through said openings and connections from said transformer to said electrodes.

In witness whereof, I have hereunto set my hand this 18th day of June, 1920.

HENRY GEISENHÖNER.
